UNITED STATES PATENT OFFICE.

JOSEPH KEPPLER, OF NEW YORK, N. Y., ASSIGNOR TO BENJAMIN T. B. HYDE, OF NEW YORK, N. Y., TRADING AS HYDE EXPLORING EXPEDITION.

DESIGN FOR A PEDESTAL OR LEG FOR FURNITURE.

SPECIFICATION forming part of Design No. 36,238, dated February 24, 1903.

Application filed January 21, 1903. Serial No. 140,034. Term of patent 7 years.

To all whom it may concern:

Be it known that I, JOSEPH KEPPLER, a citizen of the United States, residing at the city of New York, in the county and State of New York, have invented and produced a new, original, and ornamental Design for a Pedestal or Leg for Furniture, of which the following is a specification, reference being had to the accompanying drawing, forming part hereof, and which is a perspective view of the pedestal or leg, showing my new design.

As illustrated in the drawing, the leading or material feature of my design consists in the configuration or outline of the pedestal or leg, as well as the surface ornamentation thereof. In outline the pedestal or leg has an upper quadrilateral panel *a*, a central rectangular panel *b*, merging into the upper panel *a* by the angular pieces *d* and expanding at the base into a frusto-pyramidal projection *b'*. Below the projection *b'* and merging into the same are the zigzag or trapezoidal panels *e*, surmounting a frusto-pyramidal base *f*. The upper panel *a* has on its face an

ornament *a'* in the form of an Indian head. ²⁵ The angular pieces *d* are ornamented to represent uplifted arms and hands. The zigzag panels *e* are ornamented to represent legs, and the base *f* is ornamented to represent, conventionally, the Indian's moccasins or foot-gear. ³⁰ When viewed from the front, the pedestal or leg represents, conventionally, a Kat-zina or Indian god. Upon the panel *a*, adjacent to the head *a'*, are arranged symbolic ornaments *a²* and *a³*. ³⁵

Having thus described my invention, what I claim as new, and desire to secure by Letters Patent, is—

The ornamental design for a pedestal or leg for furniture, substantially as herein shown ⁴⁰ and described.

In testimony whereof I have hereunto set my signature in the presence of two subscribing witnesses.

JOSEPH KEPPLER.
